UNITED STATES PATENT OFFICE.

WALTER S. LEVIN, OF SAN FRANCISCO, CALIFORNIA, ASSIGNOR TO THE NATIONAL SAFETY APPLIANCE COMPANY, OF SAN FRANCISCO, CALIFORNIA, A CORPORATION OF CALIFORNIA.

TRACK-OPERATED DEVICE FOR AUTOMATIC BLOCK-SIGNAL SYSTEMS.

1,305,384.

Specification of Letters Patent.

Patented June 3, 1919.

Application filed April 24, 1917. Serial No. 164,135.

To all whom it may concern:

Be it known that I, WALTER S. LEVIN, a citizen of the United States, and a resident of San Francisco, city and county of San Francisco and State of California, have invented a certain new and useful Improvement in Track-Operated Devices for Automatic Block-Signal Systems, of which the following is a specification.

10 The object of my invention is to provide a make and break track device which is simple in construction, of few parts and certain and efficient in its operation.

The track device constitutes in its broadest 15 aspect a simple circuit breaker operated by the depression of the rail as the train passes over it.

Referring to the drawings:

Figure 1 is a diagrammatic view of that 20 portion of a block signal system including a line of track magnet, a make and break track device and an improved time limit relay controlled by a magnet which is in the circuit with the make and break device 25 forming the subject matter of the present invention.

Fig. 2 is a vertical transverse section of a rail and portions of my improved make and break track device, other portions being shown in elevation.

Fig. 3 is a section on line 3—3 of Fig. 2, the circuit wire being omitted.

Referring to Fig. 1 of the drawings, 70 represents the track device forming an element in a signaling system disclosed in my application for a patent for improvements in automatic block signal systems filed on April 24, 1917, under Serial No. 164,134.

So far as the present invention is concerned, it is only necessary, referring to Fig. 1, to note that 70 is the track device, 56 is the lever thereof, T a rail of the track, 59 a battery energizing the circuit in which is included the track device, 1 a magnet and 45 10 an armature for the magnet.

The circuit is as follows:—

Starting at the battery 59 by wire 58 to the short arm 8 of the track device, lever 56, contact 19, wire 61 to magnet 1, wire 60 to 50 battery, thus completing the circuit.

The construction of the make and break track device 70 is shown in Figs. 2 and 3. T is the rail, 2 a hardened steel member

convex at its upper end and concave at its lower end, which member is attached to the 55 center of the flexible rubber diaphragm 5 by means of the metal ring 3 and screws 4, the diaphragm being in turn attached at its periphery to the containing case by the metal ring 6 and screws 7. The lower end of the 60 hardened steel member 2 bears on the end 8 of the lever 56 which is mounted on a shaft 14, the lever being fitted with bronze bushings 15. The arm 56 of the lever is provided with a screw-threaded stop 25 passing 65 therethrough and held in its adjusted position by a lock nut 16, the said stop being provided for adjusting the downward travel of the lever. Projecting from the end of the lever and substantially in line therewith 70 is a pin 18 fitted thereto and arranged to make contact between the spring contact arms 19 and 20. These springs are mounted on a support 23 which is carried on the studs 21 and 22, the springs being insulated 75 from the support 23 and provided with a binding post 24. 17 is the base for carrying the device and 12 is a support insulated at 17' from the base 17. This support is fitted at one end with a binding post 13 and at 80 the other end with a binding post 11 to which is attached a flexible copper lead 10 which is riveted or otherwise secured to a terminal 9 on the arm 8 of the lever.

The lever is included in the operating circuit so that in the event that it should be fractured from any cause (which danger is extremely remote), it would open the operating circuit of the relay and display the necessary stop signals; hence the insulation 90 from the base at 17' as above referred to.

In operation, as the track is depressed by a passing train, it depresses the hardened steel member 2 which in turn depresses the lever arm 8 causing the lever to rock on the 95 shaft 14 and the projecting end 18 to rise and break contact with the springs 19 and 20, thus opening the circuit and causing the magnet 1 of the time limit relay as shown in Fig. 1 to be deenergized and thus causing the time limit relay to operate.

Having now described my invention, what I claim as new and desire to secure by Letters Patent is:

1. In a track device for an automatic 105 train signal system, the combination with

- the rail, of a lever mechanically connected therewith, an electrical contact normally engaged by the lever at one end thereof, and an electric circuit connected to said contact 35
- 5 and to the end of said lever remote from said contact, the said lever normally forming a portion of said circuit.
2. In a track device for an automatic train signal system, the combination with 40 the rail, of a lever pivoted at a point intermediate its ends, one end of said lever being mechanically connected to the rail, a contact normally engaged by the other end of 45 said lever, and an electric circuit connected 10 to said contact and to the lever end adjacent the rail, the said lever normally forming a portion of said circuit.
3. A track device for an automatic train signal system, consisting of a lever, one arm 50 of which is connected to the track, and the other arm constituting a make and break element, a flexible diaphragm, a wear resisting element carried by the diaphragm and situated between the rail arm and the 55 arm of the contact lever, and an electric circuit permanently connected to the first mentioned lever arm and normally connected to the other lever arm.
4. In a track device for an automatic 60 train signal system, the combination with the rail, of a relay operating normally closed circuit, and a lever having two arms included in said circuit, said lever being mechanically connected to the rail and

adapted to break said circuit electrically both upon the rail being depressed and upon the accidental mechanical breaking of the lever.

5. In a track device for an automatic train signal system, the combination with 40 the rail, of a relay operating circuit, a rocking lever, a flexible diaphragm, a wear resisting element carried by said diaphragm and interposed between the rail and one end of said lever, a base carrying said lever, 45 a contact adapted to coöperate with the free end of said lever, and binding posts connected to said circuit and insulated from said base, one of said binding posts being connected to said contact and the other to the lever end adjacent the rail. 50

6. In a track device for an automatic train signal system, the combination with 55 the rail, of a lever having one end connected to the rail, an electric contact normally engaged by the other end of said lever, binding posts respectively connected to said contact and to the lever end adjacent the rail, and means for adjusting the lever in position relatively to said contact. 60

Signed at borough of Manhattan, city and State of New York, this nineteenth day of April, 1917.

WALTER S. LEVIN.
